United States Patent Office

Des. 199,877
Patented Dec. 22, 1964

199,877

DOOR CHIME

Norman William Stevenson, Rainow, Macclesfield, England, assignor to V. & E. Friedland Limited, Macclesfield, England, a British company

Filed Apr. 30, 1963, Ser. No. 74,714

Claims priority, application Great Britain Dec. 7, 1962

Term of patent 14 years

(Cl. D72—1)

FIGURE 1 is a front perspective view from above and one side of a door chime showing my new design,

FIGURE 2 is a rear perspective view from below and the other side,

FIGURE 3 is a front elevation, and

FIGURE 4 is a section on line 4—4 of FIGURE 3.

I claim:

The ornamental design for a door chime, substantially as shown.
